UNITED STATES PATENT OFFICE.

HUBERT ROSS ESTES, OF CHICAGO, ILLINOIS.

ADVERTISING DEVICE.

Application filed October 20, 1924. Serial No. 744,774.

To all whom it may concern:

Be it known that I, HUBERT ROSS ESTES, a citizen of the United States, and a resident of Chicago, county of Cook, State of Illinois, 5 have invented a new and useful Improvement in Advertising Devices, of which the following is a full, clear, and exact description.

My invention relates to improvements in 10 advertising devices, and it consists in the combinations, constructions, and arrangements herein described and claimed.

An object of my invention is to provide an 15 advertising device which has movable members that are adapted to be actuated by the wind and which may be highly colored so as to attract the attention of passersby to the advertisement carried by the device.

A further object of my invention is to 20 provide a device of the type described which makes use of an advertising medium that may have the advertising matter printed thereon, this medium being shaped so as to more clearly convey the purpose of the ad- 25 vertisement.

A further object of my invention is to pro- 30 vide a device of the type described in which the advertising medium may be secured to the device so as to remain in a stationary position, or which may be adjusted so as to 35 be moved by one of the wind actuated members.

A further object of my invention is to pro- 35 vide a device of the type described which is especially designed so as to be shipped in a compact bundle, and then assembled upon its arrival at the destination.

A further object of my invention is to pro- 40 vide a device of the type described which is simple in construction, durable, and efficient for the purpose intended.

Other objects and advantages will appear 45 in the following specification, and the novel features of the invention will be particularly pointed out in the appended claims.

My invention is illustrated in the accom- 50 panying drawings, forming part of this applica-
tion, in which—

- Figure 1 is a side elevation of the device,
- 50 Figure 2 is a plan view of the device,
- Figure 3 is a section along the line 3—3 of Figure 2,
- Figure 4 is a section along the line 4—4 of Figure 2, and
- 55 Figure 5 is a modified form of the supporting means for the device.

In carrying out my invention I provide a supporting base 1 which may be secured to a post 2 or the like by means of screws. The supporting member 1 has a sleeve 4 therein 60 which is adapted to receive the lower end of an upright 5. The upright 5 in the present instance is in the shape of a rod and is secured to the support 1 by means of a set screw 6.

The rod is adapted to carry wind wheels indicated generally at A and B. The wheels are constructed so as to rotate in opposite directions so as to attract the attention of passersby. Since the wheels A and B are 70 identical in construction, it will be sufficient to describe the wheel A. The wheel consists of an upper plate 7 and a lower plate 8, which are provided with projections 9 that have grooves 10 therein. The projections 9 with the grooves 10 are clearly shown in Figures 3 and 4. In the present form of the device I have shown four of the projections 9 on each of the plates 7 and 8. The vanes 11 of the wind wheel are curved as 80 shown in Figure 2 and are provided with wire arms 12 which are adapted to be inserted in openings 13 in the plates 7 and 8, and then be bent from the dotted line position shown in Figure 4 into the full line position shown, so as to lock the vanes in place. The plates 7 and 8 are loosely mounted upon the rod 5 and the plate 7 is kept 85 spaced from the plate 8 by means of a bend 14 in the arms 12.

Each vane consists of a plate 15 and arms 12. The arms 12 extend the entire length of the vane, and the ends of the plate 15 are bent around the arms whereby the plate is secured to the arms. The wire arms 12 are 90 curved so as to give a curvature to the plate 15 as clearly shown in Figure 2. The plates 15 space the arms 12 of each plate away from each other, and the arms 12 in turn space the plates 7 and 8 from each other. The plate 8 100 is rotatably carried by means of a bushing 16 which is loosely mounted upon the rod 5. A pin 17 is carried by the rod 5 and supports the bushing 16. It will be seen from this construction that the wind wheels are 105 adapted to rotate freely about the rod 5.

An advertising sign 18 is provided with lugs 19 that have openings 20 therein which receive the rod 5. The plate 18 is free to rotate about the rod 5. A bushing 21 is 110 mounted upon the rod 5 and supported by means of a pin 22. The pin is removably

carried by the rod 5 and when removed, permits the sign to drop down upon the wind wheel B as shown by the dotted line position in Figure 1. When the sign 18 is in full line position, the pin 22 will prevent the rotation of the sign due to the pin engaging with the wall of the opening 23 in the sign 18, as shown in Figure 2. When the sign, however, is in the dotted line position, it will be supported by the wind wheel B, and will be carried around by the rotation of the wind wheel.

From the foregoing description of the various parts of the device, the operation thereof may be readily understood. One of the principal objects or advantages of the device lies in the fact that it can be packed into a small bundle for shipment. In Figure 4 I have shown that the arms 12 may be bent so as to secure the arms to the plates 7 and 8. When shipping the device, the vanes 11 are nested, and therefore occupy a very small space. The support 1 may also be removed from the rod 5 and in like manner the sign 18 may be removed from the rod 5. The parts when disassembled may be packed into a small space for shipment.

The person when assembling the device inserts the ends 23 of the arms 12 through the openings 13 in the plates 7 and 8. This movement causes the arms to be received in the grooves 10. The arms are now bent as shown in Figure 4, thus completing the construction of the wind wheel. The projections 9 are long enough to prevent the vanes from swinging with respect to the plates 7 and 8. The vanes, together with the plates 7 and 8 form a single unit which is readily rotated by means of the wind. The plates 15 may be colored in different bright colors so as to attract attention. The vanes of the wind wheel A are curved differently from the vanes of the wind wheel B, and thus the wheels rotate in opposite directions. The device is especially designed to be placed on fence posts or the like along country roads, where they may be readily viewed by the passerby.

If it is desired to secure the device to a vertical wall such as that shown by 30 in Figure 5, I provide an L-shaped bracket 31 which is adapted to be secured to the wall 30 by means of screws 32. The horizontal arm 33 of the bracket is provided with a socket 34 which receives the lower end of the rod 5. A set screw 35 secures the rod in place. The device is extremely simple in operation and provides a novel and efficient means for attracting the attention of

passersby. As heretofore stated the sign 18 may be shaped so as to suggest the article which is being advertised.

I claim:

1. An advertising device comprising a supporting rod, wind actuated members rotatably carried by said supporting rod, an advertising medium carried by said rod, and means for preventing the rotation of said medium, said means being removably secured to said rod to permit said sign to be supported, and actuated by one of said wind actuated members when said means is removed.

2. An advertising device comprising a supporting rod, wind actuated members rotatably carried by said supporting rod, an advertising medium carried by said rod, and means for preventing the rotation of said medium, said means being removably secured to said rod to permit said sign to be supported, and actuated by one of said wind actuated members when said means is removed, said wind actuated members being constructed so as to rotate in opposite directions with respect to each other.

3. An advertising device comprising a rod, wind wheels rotatably carried by said rod, vanes carried by said wind wheels, and being removably secured thereto, an advertising sign carried by said rod, means for preventing the rotation of said sign, said means being removably secured to said rod so as to permit the sign to drop down upon one of the wind wheels, whereby said sign is rotated by means of said wind wheel.

4. An advertising device comprising a rod, a support for said rod, wind wheels carried by said rod, vanes removably secured to said wind wheels and constituting a part thereof, an advertising sign carried by said rod, a pin for supporting said sign on said rod and preventing the rotation of said sign, said pin being removably secured to said rod so as to permit the sign to rest upon one of the wind wheels and be rotated thereby.

5. An advertising device comprising a supporting member, wind actuated members rotatably carried by said first named member, an advertising medium carried by said first named member, and means for preventing the rotation of said medium, said means being removably secured to said first named member to permit said medium to be supported and actuated by one of said wind actuated members when said means is removed.

HUBERT ROSS ESTES.
